CORN POPPER

Filed Dec. 27, 1943

UNITED STATES PATENT OFFICE

2,505,967

CORN POPPER

Ralph P. Humphrey, Liberty, Mo.

Application December 27, 1948, Serial No. 67,407

7 Claims. (Cl. 259—122)

1

This invention relates to corn popping devices and is an improvement on the construction disclosed and claimed in my copending application, Serial No. 729,095, filed February 17, 1947, and has for its principal object to provide a simplified structure to facilitate manufacture and assembly of the respective parts.

In accomplishing this and other objects of the invention as hereinafter pointed out, I have provided a structure illustrated in the accompanying drawing wherein:

Fig. 1 is a perspective view of a corn popper embodying the features of the present invention.

Fig. 2 is an enlarged vertical section through the popper.

Fig. 3 is a perspective view of the agitator parts shown in disassembled relation to better illustrate the construction thereof.

Referring more in detail to the drawing:

1 designates a corn popper constructed in accordance with the present invention and includes a sauce pan-shaped vessel 2 having a handle 3 projecting from a side thereof. The vessel 2 has a substantially flat bottom 4 and an annular wall 5 terminating in an outset rim 6 encircling an inset seat 7 for seating and axially retaining a lid or cover 8.

The lid 8 preferably has a crowned top 9 having a rolled edge 10 engaging the seat 7 and inner face 11 of the pan rim. The lid is thus retained on the vessel and forms a mounting for the agitator mechanism 12 by which the salt and grease are mixed with the pop corn kernels and the kernels of corn are stirred and kept in agitation during popping as later described.

The agitator includes a wire-like shaft 13 adapted for rotary support in a bearing member 14 carried by the lid 8. The lower end of the shaft is provided with a bearing portion 15 which seats on the bottom 4 under weight of the shaft and carries a laterally directed stirring arm 16. The bearing portion of the shaft and arm 16 is formed by bending the wire-like material in a slightly lateral direction as indicated at 17 and then in a substantially semi-circular reverse curve 18 to bring a bottom contact portion 19 coaxial with the shaft. The terminal of the reverse curve is carried above the contact portion 19 and curves as at 20 into the arm 16 whereby the arm sweeps in a plane slightly above the bottom 4 of the vessel (see Fig. 2).

The bearing member 14 is formed of a single part and has a cylindrical body portion 21 having a neck 22 at one end which is of reduced diameter to provide an annular shoulder 23

which seats upon the top 9 of the lid 8 when the neck 22 is passed through an axial opening 24 of the lid. The neck 22 has external threads 25 for a nut 26 that is turned thereon to cooperate with the shoulder 23 in clamping the lid therebetween for securing the bearing member rigidly to the lid. The cylindrical body of the bearing member has an external annular groove 27 that is spaced above the lid and shoulder 23. The upper end of the cylindrical body 28 is preferably rounded in conformation with the dome-like top 9 of the lid 8. The bearing member has an axial bore 29 extending therethrough of suitable size to loosely and slideably journal the shaft since it is desirable that the shaft float freely in the bearing to avoid pressure on the bottom of the vessel and prevent wedging of kernels under the arm of the agitator, as well as to conform to any variation in the bottom of the vessel.

The bearing member also rotatably mounts a crank 30 by which the agitator shaft is rotated while allowing floating movement thereof. The crank includes a plate-like arm 31 formed as a die stamping with an offset 32 between the attaching end 33 and knob carrying end 34. The end 33 has a thickness to enter freely into the groove 27 and is provided with a notch 35 forming a semicircular face 36 and tines 37 and 38 for engaging sides of the bearing member at the base of the groove 27.

In order to connect the agitator shaft slidably with respect to the crank and to retain the crank on the bearing member, the upper end 35 of the agitator shaft has a goose neck 40 to provide a depending terminal 41 which slides through an opening 42 in the crank arm as shown in Fig. 2. To limit sliding movement of the shaft and prevent withdrawal of the terminal 41, the shaft is provided above and below the bearing member with stops 43 and 44 that may be formed by means of a staking operation.

The terminal end of the crank carries a knob 45 that is journaled thereon by means of a rivet 46 having a shank 47 extending loosely through an opening 48 in the arm and fixed in a socket 49 of the knob 45.

In assembling the agitator one end of the shaft, before bending, is passed through the bore 29 of the bearing member, for example, the end on which the goose neck 40 is to be formed. The goose neck is then shaped to provide the driving terminal 41. The crank carrying the knob 45 is then applied to the bearing member by sliding the tines 37 and 38 into the groove 27

until the semi-circular face 36 of the notch seats against the bottom of the groove 27 whereupon the shaft is shifted in the bore of the bearing member to engage the terminal 41 in the opening 42 of the crank arm. The shaft is then staked to form the stops 43 and 44, the staking operations being applied at points on the shaft so that when the lid 8 is off of the vessel 2 the terminal 41 will not scar the crowned top 9 of the lid as the stop 43 engages the end 28 of the bearing member, and the terminal will be retained in the opening 42 of the crank arm when the stop 44 engages the threaded neck 22 regardless of whether the lid is on or off the vessel.

The agitator assembly is mounted on the lid by passing the threaded neck 22 through the opening 24 and the nut 26 is applied to draw the shoulder 23 into engagement with the upper face of the lid or cover.

In using the popper, the kernels of corn are placed in the vessel and the lid carrying the agitator is placed over the vessel with the bead thereof engaging the seat 7 within the embrace of the rim 6. The crank is then rotated to agitate the corn during popping. It is obvious that the terminal 41 of the goose-neck forms a driving connection between the shaft and crank and also retains the crank from sliding out of the groove 27 when the crank is turned about the bearing member. During turning of the crank the contact or bearing point 19 of the agitator rests freely and rides smoothly without wear upon the pan bottom and the arm sweeps thereabove without scraping or wedging of the kernels.

Since the lid fits relatively tight, a side thereof which is turned away from the handle 3 may be provided with vent openings 50 as shown in Fig. 1 for escape of any steam generated during a popping operation.

From the foregoing it is obvious that I have provided a simple and inexpensive structure that is readily assembled and which operates efficiently. The structure accomplishes the desired results with a minimum of parts and the parts required are easily manufactured.

It is also obvious that the agitator shaft and crank arm slide within the bearing member 14 and that any movement thereof does not affect the pan covers retention on pan or movement of the crank. Finger pressure on handle knob is transmitted directly to the bearing member, and from the bearing member directly to pan cover, in a retention capacity, and does not reflect on the agitator. In other words, there is nothing tending to displace the lid of the vessel.

What I claim and desire to secure by Letters Patent is:

1. In a device of the character described, a bearing member having an axial bore and an external circumferential groove, a crank arm having one end freely engaged in the groove and adapted to be gyrated around said bearing, and a shaft extending through the bore of the bearing member and having a terminal slidably engaged with the crank arm for forming a driving connection between the crank arm and said shaft and for retaining the crank arm on the bearing member.

2. In a device of the character described, a bearing member having an axial bore and an external circumferential groove, a crank arm having one end provided with a notch to pass the crank onto the bearing member and provide

tines engaging opposite sides of the bearing member for forming a journal for the crank arm, a shaft slidably rotatable in said bore of the bearing member, and a goose-neck on the end of the shaft having a terminal parallel with the shaft and slidable within an opening in the crank arm for forming a driving connection between the shaft and crank and for retaining the crank arm on the bearing member.

3. In a device of the character described, a bearing member having an axial bore and an external circumferential groove, a crank arm having one end provided with a notch to pass the crank onto the bearing member and provide tines freely engaging opposite sides of the bearing member for forming a journal for the crank arm, a shaft slidably rotatable in said bore of the bearing member, a goose-neck on the end of the shaft having a terminal parallel with the shaft and slidable within an opening in the crank arm for forming a driving connection between the shaft and crank and for retaining the crank arm on the bearing member, and stops on the shaft at respective ends of the bearing member to limit movement of said terminal in the crank arm.

4. A corn popper comprising a vessel, a lid for the vessel having an axial opening, a bearing member having a reduced externally threaded neck extending through said axial opening of the lid and providing a shoulder engaging the lid, a nut on the threaded neck to cooperate with the shoulder for securing the bearing member to the lid, said bearing member having an axial bore and an external annular groove, a crank arm having one end freely engaged in the groove and adapted to be turned around the bearing member, a shaft extending slidably through the bore of the bearing member and having a 35 goose-neck terminal slidably engaged within an opening in the crank arm for forming a driving connection between the crank arm and said shaft and for retaining the crank arm on the bearing member, and a stirring arm on the shaft and 40 movable over the bottom of the vessel upon turning of the crank about the bearing member.

5. A corn popper comprising a vessel, a lid for the vessel having an axial opening, a bearing member having a reduced externally threaded neck extending through said axial opening and providing a shoulder engaging the lid, a nut on the threaded neck to cooperate with the shoulder for securing the bearing member to the lid, said bearing member having an axial bore and an external annular groove, a crank arm having one end freely engaged in the groove and adapted to be turned around the bearing member, a shaft extending slidably through the bore of the bearing member and having a goose-neck terminal 55 slidably engaged within an opening in the crank arm for forming a driving connection between the crank arm and said shaft and for retaining the crank arm on the bearing member, a stirring arm on the shaft and movable over the bottom of the vessel upon turning of the crank about the bearing member, and a stop on the shaft adapted to engage said neck to retain the goose-neck terminal in driving connection with the crank arm and limit said sliding movement of the shaft.

6. A corn popper comprising a vessel, a lid for the vessel having an axial opening, a bearing member, means for securing the bearing member rigidly to the lid in coaxial alignment with said opening, said bearing member having an axial bore and an external annular groove, a crank

arm having one end freely engaged in the groove and adapted to be turned around the bearing member, a shaft extending slidably through the bore of the bearing member and having a goose-neck terminal slidably engaged within an opening in the crank arm for forming a driving connection between the crank arm and said shaft and for retaining the crank arm on the bearing member, and a stirring arm on the shaft and movable over the bottom of the vessel upon turning of the crank about the bearing member.

7. A corn popper comprising a vessel, a lid for the vessel having an axial opening, a bearing member, means for securing the bearing member to the lid, said bearing member having an axial bore and an external annular groove spaced from the lid, a crank arm having one end provided with a notch to pass the crank arm into engagement with the groove for free turning movement around the bearing member, a shaft extending 20 slidably through the bore of the bearing member and having a goose-neck terminal slidably en-

gaged within an opening in the crank arm for forming a driving connection between the crank arm and said shaft and for retaining the crank arm on the bearing member, a stirring arm on the shaft and movable over the bottom of the vessel upon turning of the crank about the bearing member, and a stop on the shaft and located in spaced relation with the vessel side of the lid to retain the goose-neck terminal in driving connection with the crank arm and limit said sliding movement of the goose-neck terminal.
